UNITED STATES PATENT OFFICE.

ALBERT P. OLMSTEAD, OF TROY, NEW YORK.

COMBINED HASP AND BOLT.

SPECIFICATION forming part of Letters Patent No. 319,014, dated June 2, 1885.

Application filed June 23, 1884. (No model.)

To all whom it may concern:

Be it known that I, ALBERT P. OLMSTEAD, of the city of Troy, county of Rensselaer, State of New York, have invented a new and useful Improvement in Combined Door or 5 Gate Hasp and Bolt, of which the following is a specification.

My invention relates to hasps—a class of devices that are used on doors or gates to fasten them. These articles as usually made are constructed with an eye at one end, through which a clinching-staple is passed to secure the device to the door or door-jamb, with the other end made to have an elongated eye arranged 15 to pass over the eye of a secured staple, so that a padlock or pin may be passed into the latter outside the hasp.

My improvement on this class of devices consists, as will be more fully detailed hereinafter in connection with its illustration, in the combination, with a hasp made to be secured to the door or door-jamb at one end by an eye on the hasp, and a clinching-staple, of a spring-bolt attached to the outside of the hasp, an 25 elongated slot arranged in the free end of the hasp, and a staple attached to the door or jamb and provided with a lower eye for the bolt on the hasp, and an outer eye for the padlock.

Accompanying this specification, to form a 30 part of it, there is a sheet of drawings containing two figures illustrating my invention and improvement, with the same designation of its parts by letter-reference used in both of them. Of these illustrations, Figure 1 shows a perspective of a hasp containing my invention, and Fig. 2 shows a longitudinal section of the same.

The several parts of the hasp and the features containing my improvement and invention are designated by letter-reference, and the function of the parts is described as follows:

The letter H designates the hasp-body made with an attaching-eye, E, at one end, adapted 45 to be secured to the door or door-jamb thereat by a staple, T.

The letter B designates a latch-bolt, and C the housing for the bolt attached to the hasp. The bolt on the under side is recessed at R to 50 receive a spring, S, and this spring has a guide-

rod, g, that is parallel to and arranged within the recess R in the side of a lug, p, projected from the face of the hasp up into the recess R, that is made in the bolt. The rear end of the bolt-latch B is made with an outwardly-projected finger-piece, F, for pulling it out. The latch end of the bolt on its face nearest the hasp is rounded off, as indicated at m.

The letter d designates a bolt-stop on the face 60 of the hasp.

As thus constructed, the bolt B is adapted to be drawn out against the force of the spring S by means of the finger-piece, and to be automatically returned when the tension on the finger-piece is released.

The letter E² indicates an eye or slot formed in the hasp at its free end at right angles to its sides, and D designates a staple adapted to be attached to the door-jamb or door by means of screws L on the staple-plate P'. The face 70 of this staple D has two openings or eyes, O' and O². The lower one, O², is adapted to receive the latch end of the bolt, and the outer one, O', is adapted to receive a padlock when the hasp, by means of its eye E², is passed over 75 the said staple D.

The dotted line d' designates the hasp as detached from the staple D and as swung down on its staple-connection at T.

The parts thus made and arranged are used 80 as follows: The hasp being attached to the door M at its eye end E, and the staple D being attached to the door-jamb J by means of screws in the staple-plate P', when the hasp is, by means of its eye E², passed over the said 85 staple D and pressed in against the door, the bolt latches into the lower opening, O², being forced there by the spring S, and this fastens the door by the bolt-latch. When it is desired to lock the door from the outside, so that 90 it cannot be opened without unlocking it, a padlock is inserted in and locked in the opening O'.

Having thus described my invention, what I claim, and desire to secure by Letters Patent, 95 is—

In a door or gate hasp, the combination of the hasp-body constructed with an eye for pivotal attachment at one of its ends, and made with an eye or slot to receive a staple at the 100

other end, a latch-bolt and spring arranged on the outer face of the said hasp within a housing or side inclosure thereon, a staple adapted to be attached to a door-jamb and to receive 5 the free eye end of the hasp when passed over it, an upper and a lower opening in said staple, with the lower opening adapted to receive said bolt-latch, as shown and described.

Signed at Troy, New York, this 31st day of May, 1884, in the presence of the two witnesses whose names are hereto written.

ALBERT P. OLMSTEAD.
